UNITED STATES PATENT OFFICE

2,007,904

MINING MACHINERY

Albert C. Wilcox, Bridgeport, Ohio, assignor to
Sullivan Machinery Company, a corporation of
Massachusetts.

Application September 17, 1931, Serial No. 563,367

85 Claims. (Cl. 262—28)

This invention relates to mining machines, and more particularly to improvements in coal mining machines of the combined horizontal and shear cutting, wheel mounted type adapted to operate from the mine trackway.

An object of this invention is to provide an improved coal mining machine. Another object is to provide an improved coal mining machine of the combined horizontal and shear cutting type having improved adjustable supporting means for the cutting mechanism. A further object is to provide an improved coal mining machine having improved kerf cutting mechanism whereby a horizontal kerf of substantially uniform depth may be cut entirely across the coal face. Yet another object is to provide an improved coal mining machine having improved adjustable kerf cutting mechanism whereby both horizontal and vertical cuts may be made and whereby a horizontal cut may be formed of substantially uniform depth entirely across the coal face. A still further object is to provide improved kerf cutting mechanism for a coaling mining machine wherein a rotatable cutter head is employed for adjusting the kerf cutter into horizontal and vertical cutting positions, and including an improved adjustable supporting structure for the cutter head whereby the latter may be adjusted laterally into various operating positions while the head axis is maintained parallel to the longitudinal axial line of the machine. Another object is to provide improved means associated with the supporting means aforesaid for adjusting the cutter head to change the angular relation of its axis relative to the longitudinal axial line of the machine. Another object is to provide an improved parallel motion supporting structure for the rotatable cutter head. Still another object is to provide an improved coal mining machine having improved cutting mechanism capable of forming straight face cuts across the coal face. A still further object is to provide an improved coal mining machine of the combined horizontal and shear cutter type having improved adjustable supporting means for the cutting mechanism whereby vertical kerfs may be inserted in the coal face at any desired location between the ribs, and a horizontal kerf may be inserted in the coal face at a certain level. These and other objects and advantages of this invention will, however, hereinafter more fully appear in the course of the following description and as more particularly pointed out in the appended claims.

55 In the accompanying drawings there is shown,

for purposes of illustration, one form which the invention may assume in practice.

In these drawings.—

Fig. 1 is a side elevational view of the illustrative embodiment of the improved coal mining machine.

Fig. 2 is a rear end elevational view of the machine.

Fig. 3 is a front end elevational view of the machine.

Fig. 4 is a top plan view showing by dotted lines the manner in which the cutter element is caused to traverse a substantially straight line, as distinguished from swinging in the arc of a circle when making a horizontal or under cut.

Fig. 5 is an enlarged central vertical sectional view taken substantially on line 5-5 of Fig. 4.

Fig. 6 is a horizontal sectional view taken substantially on line 6—6 of Fig. 5.

Fig. 7 is a transverse vertical sectional view taken substantially on line 7—7 of Fig. 1.

Fig. 8 is a horizontal sectional view taken substantially on line 8—8 of Fig. 5. Fig. 9 is an enlarged vertical sectional view taken through the improved adjustable supporting means for the cutting element and illustrating the manner in which the cutting element is driven. 25

Fig. 10 is a transverse vertical sectional view taken substantially on line 10—10 of Fig. 9.

Fig. 11 is an enlarged top plan view of the supporting means for the cutting element shown in Fig. 9.

Fig. 12 is a transverse vertical sectional view taken substantially on line 12-12 of Fig. 9. Fig. 13 is a view similar to Fig. 11 showing how the cutting element may be swung horizontally to different angular positions with respect to the body of the machine.

Fig. 14 is a detail view illustrating a portion 40 of the swinging means.

Fig. 15 is an enlarged side elevational view of the cutter head which carries the cutting element, showing the latter in full and dotted lines in the different positions it occupies when making a vertical or shearing cut. 45

Fig. 16 is a detail sectional view taken substantially on line 16-16 of Fig. 7.

In this illustrative embodiment of the invention, there is shown a coal mining machine of the combined horizontal and shear cutting, wheel mounted type adapted to operate from the mine trackway and generally comprising a frame or body 1 mounted on wheels 2 adapted to travel along a mine trackway 3. Supported on the 55

frame or body 1, through improved adjustable supporting means 4, is a rotatable cutter head 5 having pivotally mounted thereon a kerf cutting element 6. The frame or body 1 consists of a base portion 7 having a rearward upstanding portion or standard 8 from which there projects a horizontal arm-like portion 9, the latter extending forwardly from the standard 8 and overlying the base portion 7 in the manner shown. Pivotally mounted at 10 on the forward extremity of the arm-like portion 9 is a block member 11. This block member is provided with a cylindrical projection 12 forming a journal, and is retained in position within a bore 13 formed in the arm, by means of a retaining nut 14 threadedly connected to the projection 12. As shown, pivotally connected to the block member 11 at 15, 15 are spaced parallel arms 16, 16, in turn pivotally connected at 17, 17 to and supporting a plate 18. Also pivotally connected to this plate member about axes coincident with the axes of the arms 16, 16 are spaced parallel arms 19, 19, in turn pivotally connected at 20, 20 to a frame member 21. The two pairs of arms 16, 16 and 19, 19 in conjunction with the block 11, plate 18 and frame member 21, constitute a double parallelogram structure by which the frame member 21 with its attached parts is mounted on the arm-like portion 9 of the machine body. As shown in Fig. 11, the frame member 21 is provided with a cylindrical bearing portion 22, herein in the form of a neck, on which the cutter head 5 is rotatably mounted. From the foregoing it will be evident that the parallel frame structure maintains the axis of the cutter head always parallel to a common straight line during swinging of the arm structure transversely across the machine; and to permit the axis of the cutter head to be disposed angularly with respect to said common straight line, there is provided means for rotating the block member to change the spacial relation of the arms as shown in Fig. 13. The rotating means for this block member comprises a worm wheel 23 keyed at 24 to the block member and with which meshes a worm 25. The worm 25 is fixed to a horizontal shaft 26 arranged transversely of and suitably journaled within bearing brackets 27, attached to the arm-like portion 9 of the machine frame. Suitably fixed to the shaft 26 is a hand wheel 28. As the hand wheel 28 is rotated, the block member 11 is rotated through the worm gearing, and this rotative movement of the block member is transmitted through the parallel arms 16, 16 to the plate 18 and the parallel arms 19, 19 to the frame member 21, causing the latter to be tilted laterally in one direction or the other to change the angular position of the cutter head axis. The worm gearing 24, 25 is of the self-locking type and maintains automatically the parts in their adjusted position.

Now referring to the improved motor operated devices for actuating the cutting element, it will be noted that arranged within the rearward portion of the machine frame is a motor 30, herein preferably of the reversible electric type having its power shaft 31 horizontally disposed and extending longitudinally of the machine. Fixed to the forward end of the motor power shaft is a worm 32 meshing with a worm wheel 33, in turn fixed to a horizontal shaft 34. The shaft 34 is arranged transversely of the machine frame and is suitably journaled therein and has fixed thereto at one end thereof a chain sprocket 35 which drives, through an endless chain connection 36, a sprocket 37 fixed to a horizontal shaft 38,

herein arranged parallel with and above the shaft 34. As shown in Fig. 7, splined to the shaft 36 are bevel gears 39, 40, and these gears are adapted to mesh with a bevel gear 41 to effect rotation of the latter selectively in either of opposite directions. The mechanism for shifting the bevel gears 39, 40 alternatively into meshing engagement with the bevel gear 41, comprises shipper yokes 42, 43 suitably fixed to a horizontal actuating shaft 44 slidably mounted within the machine frame and provided with a pivoted operating lever 45. As shown in Fig. 5, the bevel gear 41 is suitably fixed to the rear end of a longitudinally extending shaft 46, and fixed to the forward end of this shaft is a bevel gear 47 constantly meshing with a bevel gear 48, in turn suitably fixed to a vertical shaft 49. The shaft 49 is arranged with its axis coincident with the axis of rotation of the block member 11 and is suitably journaled within this block member in the manner shown. Suitably fixed to and driven by the shaft 49 is a bevel gear 50 constantly meshing with a bevel gear 51 suitably fixed to a horizontal shaft 52, the latter being arranged with its axis parallel with and midway between the arms 16, 16, as shown in Fig. 11. The shaft 52 is journaled at its opposite ends with bearing brackets or blocks 53, 54, the bearing bracket 53 being rotatably mounted on the shaft 49, while the bearing bracket 54 is rotatably mounted on a vertical shaft 55 carried by the plate member 18. Suitably secured to and driven by the shaft 52 is a bevel gear 56 constantly meshing with a bevel gear 57 suitably fixed to the shaft 55. Also fixed to and driven by the shaft 55 is a bevel gear 58 constantly meshing with a bevel gear 59 suitably fixed to a horizontal shaft 60, herein arranged parallel with and midway between the arms 19, 19. The shaft 60 is journaled within a bearing bracket or block 61 rotatably mounted on the shaft 55 and a bearing bracket or block 62 rotatably mounted on a vertical shaft 63 journaled within the frame member 21. Suitably fixed to and driven by the shaft 60 is a bevel gear 64 constantly meshing with a bevel gear 65 suitably fixed to the shaft 63, and this bevel gear constantly meshes with and drives a bevel gear 66 suitably fixed to a horizontal shaft 67 extending through the neck along the axis of the cutter head. Suitably fixed to and driven by the shaft 67 is a bevel gear 68 constantly meshing with a bevel gear 69 suitably fixed to a shaft 70 arranged with its axis coincident with the bar pivot axis and constituting the driving shaft for the cutting element. Secured to and driven by the shaft 70 is a chain sprocket 71, which engages and drives in a well known manner an endless cutter bit carrying cutter chain 72 mounted for circulation about the margin of an elongated plane cutter bar 73 of a usual design. It will thus be seen that due to the arrangement of the transmission shafts 52, 60 and the several driving gears, the cutter chain 72 may be driven irrespective of the position of the arm structure relative to the machine frame, it being possible to swing the cutting mechanism from one side of the machine to the other while the cutter chain is continuously driven.

The means for pivotally mounting the cutter bar on the cutter head and the means for swinging the cutter bar and rotating the cutter head, will now be described. The cutter bar 73 is provided with a cylindrical projection 74 having a radial flange 75 mounted within a circular guide-way formed by an annular plate 76 suitably rigidly secured to the cutter head frame. Fixed to

the cylindrical projection 74 is a worm wheel 71 with which meshes a worm 78 suitably fixed to a transverse shaft 73. Secured to the shaft 79 is a hand wheel 80. It will therefore be evident that when the hand wheel 80 is turned the cylindrical projection 74 is rotated through the worm gearing 77, 78, thereby swinging the cutter bar 73 about its axis relative to the cutter head. The worm gearing 77, 78 is of the self-locking type and maintains automatically the cutter bar in its different positions of adjustment. The cutter head rotating means comprises a worm gear segment 81 secured to the cutter head frame and with the teeth of which meshes a worm 82 secured to a horizontal shaft 83. The shaft 83 is arranged transversely of the cutter head frame and is suitably journaled within bearing brackets 84 secured to the frame member 21. Fixed to one end of the shaft 83 is a hand wheel 85. As this hand wheel is rotated, the cutter head 5 is turned about its axis through the worm gearing 81, 82 to position the cutter bar in the horizontal cutting position, as indicated in full lines in Fig. 12, or in its opposite shearing positions, at opposite sides of the head axis, as indicated in dotted lines in that figure. Due to the fact that the neck portion of the frame member 21 is concentric with the shaft 67 it follows that the driving connection through the shafts and gears aforementioned to the chain sprocket 71 will be maintained irrespective of rotation of the cutter head about the neck axis. Likewise, due to the cutter bar being swingable about the axis of the shaft 70, it follows that the driving connection to the chain sprocket will also be maintained irrespective of any angular position to which the cutter bar may be moved with respect to the cutter head.

Now referring to the mechanism for moving the machine as an entirety along the mine trackway, it will be observed that splined to the shaft 34 at one side of worm wheel 33 is a pair of reverse bevels 86, 87, while splined to this shaft at the opposite side of the worm wheel is a pair of reverse bevels 88, 89. The bevels 86, 87 are movable into alternative meshing engagement with a bevel gear 90 fixed to a vertical shaft 91 suitably journaled within the machine frame. The bevels 88, 89 are movable into alternative meshing engagement with a bevel gear 92 fixed to a vertical shaft 93 arranged parallel with the shaft 91 and likewise suitably journaled in the machine frame. Fixed to the shafts 91 and 93, respectively, are rope winding drums 94 and 95 having wound thereupon feed cables 96 and 97. The free ends of these cables are provided with hooks 98 normally engageable within openings formed in the upper drum flanges, as shown in Fig. 7, whereby said drums with the cables wound thereon may be rotated without tendency of the cables to unwind from the drums. The sides of the machine frame are provided with openings 99 through which the free ends of the feed cables may be extended in the manner to be later described. Journaled adjacent the openings 99 are guide rolls 100, 100 around which the feed cables are adapted to pass. As shown in Fig. 7, fixed to the lower end of the shaft 91 is a bevel gear 101 with which is adapted to mesh a bevel gear 102 splined to a transverse shaft 103. Keyed to the shaft 103 is a chain sprocket 104 which drives, through an endless chain connection 105, a sprocket 106 fixed to the rear truck wheel axle 107. The mechanism for shifting the reverse bevels 86, 87 and 88, 89 into meshing engagement with their respective bevel gears 90 and 92, comprises shipper yokes 108, 109

engaging annular grooves in the hubs of the gears and rigidly fixed to a transverse actuating rod 110 suitably guided within the machine frame. The rod 110 is provided with a screw threaded portion 111 with which threadedly engages a rotatable nut 112 rotatably mounted at 112 on the frame of the machine. Secured to the nut 112 is a hand wheel 114. It will thus be seen that as one or the other of the hand wheels is rotated the rod 110 is moved axially in one direction or the other to effect the meshing engagement of one or the other of the reverse bevel gears with the driven bevel gear. The mechanism for moving the bevel gear 102 into meshing engagement with the bevel gear 101 comprises a shipper yoke 115 engaging an annular groove on the hub of the bevel gear 102 and secured to a reciprocable actuating rod 116. Pivoted connected at 117 to one end of this actuating rod is a pivoted operating lever 118. From the foregoing it will be evident that when the bevel gears 101, 102 are in meshing engagement and one or the other of the bevel gears 86, 87 is in meshing engagement with the bevel gear 90, the truck wheels may be driven in one direction or the other to propel the machine 20 bodily along the mine trackway. It will also be noted that the feed cables on the winding drums 94, 95 under certain conditions may be extended in a suitable manner forwardly and rearwardly along the opposite sides of the machine and connected at their free ends to suitable anchors, and as the drums are rotated in the proper direction the feed cables may be wound in to move the apparatus bodily along the mine trackway in the desired direction wholly independently of the truck wheel drive.

The various parts supported by the parallel motion structure, including the rotatable cutter head and pivoted cutter bar, are relatively heavy, and as the arms suspended from the arm-like portion 9 of the machine frame are incapable in themselves of supporting said parts against sagging movement, there is secured at 120 to the frame member 21 the lower end of an upstanding rod 121, which rod extends loosely through the free end of a horizontal arm 122 and has threaded thereon a hand wheel 123. The arm 122 is pivotally connected at 124 to a truck 125, which is provided with wheels 126. These truck wheels run in a suitable manner between upper and lower tracks 127 suitably secured rigidly to the top of the arm-like portion 9 of the machine frame, as shown in Fig. 1. The arm 122 and rod 121 cooperate to form an auxiliary or supplemental support for the supporting structure 4, and as this supporting structure is swung laterally the arm 122 swings about its pivot 124 on the truck while the latter traverses the tracks 127, to permit the supporting structure to be shifted while it is supported by the arm 122. The hand wheel 123 provides means for vertically adjusting the frame member 21 to eliminate possible binding of the parts connecting this frame member to the arm-like portion 9 of the machine frame.

In the present construction, pivotally connected at 130 at one end to the forward end of the machine frame, at one side thereof, is an elongated guide arm 131 carrying on its free end a guide roll 132, while similarly pivoted at 131 the other side of the machine frame is an identical arm 133 carrying at its free end a guide roll 134. Each of these arms is swingable between a position parallel to the machine frame against the side thereof, as shown in full lines in Figs. 1

and 4, to a position at, or substantially at, right angles to the machine frame, as shown in dotted lines in Fig. 4 and in full lines in Figs. 11, 13 and 14. Each of these arms, furthermore, has 5 pivoted thereto a brace 135, which may be extended at an angle to its related arm and suitably engaged at its free end with the machine frame to hold its arm in extended position with respect to the machine frame. Each of the arms 10 19, 19 of the parallel motion structure is provided adjacent the frame member 21 with an eye 136 to which the hooks 98 on the feed cables are respectively connectible, for a purpose hereinafter described.

15 The general mode of operation of the improved coal mining machine will now be described. The mining machine may be propelled along the mine trackway either forwardly or rearwardly by means of the motor 30 geared to 20 the truck wheels, or by the cable winding drums 94, 95, as conditions may determine under the control of the reverse bevels 86, 87 and 88, 89, and the sliding gear 102. When the machine is suitably positioned adjacent the coal face and 25 it is desired to undercut the wall of the coal, the operation is as follows: The hook 98 is detached from the drum flange and the feed cable 97 is extended from the drum 95, laterally through the opening 99, around the guide roll 30 100, around the guide roll 132 carried by the guide arm 131, the latter being disposed in its right angle position with respect to the machine body at that time; and the free end of this cable is connected by the hook 98 to the eye 35 136 formed on the adjacent arm 19 of the parallel motion support structure. The feed cable 97 is then slowly wound in, and as a result the support structure, together with the parts carried thereby, is swung laterally to a position adjacent the right hand rib, as indicated at A 40 in Fig. 4. Next the lever 45 is manipulated to move the gear 39 into meshing engagement with the gear 41, which, through the gearing previously described, effects actuation of the cutter chain 72 about the margin of the cutter bar 73. Then by manipulating the lever 118 the truck wheels are connected in driving relation with the motor 30, and as a result, the machine 45 is fed as an entirety along the mine trackway to cause the cutter bar to penetrate the wall of the coal. When the cutter bar has penetrated the coal to the desired depth, movement of the machine along the trackway is discontinued, and the other guide arm 133 is swung 50 outwardly to its right angle position with respect to the machine body, and the hook 98 is detached from the drum flange and the cable 97 is passed laterally through opening 99, around guide roll 100, and around guide roll 134 on the free end of the guide arm 133, and the hook 98 on the free end of the cable is engaged in the eye 136 on the adjacent arm 19 of the parallel motion support structure. The drum 94 is 55 then suitably connected in driving relation with the motor to cause the cable 96 to be wound slowly onto the drum 94, thereby causing the arm structure, together with the parts connected therewith, to move the cutter head, and consequently the cutter bar laterally with respect 60 to the machine, resulting in the cutting of a kerf of substantially uniform depth across the coal face by a single continuous operation, the cutter bar being moved from the position A indicated in Fig. 4 to the position B shown in 65 that figure. During this operation and other 70 75

operations during horizontal cutting, the cutter bar may be swung about its pivot relative to the arm structure simply by turning the hand wheel 80 of the cutter swinging mechanism.

Under certain conditions, the cutter bar 73 when in the central position indicated at C in Fig. 4 may be dumped in an endwise direction into the coal, and when the coal is penetrated to the desired depth, the feed cable 97 may be connected to the parallel motion arm structure 10 and the cutter bar moved from left to right from the position C at the center of the entry to the position indicated at A in Fig. 4 adjacent the right hand rib of the entry. Thereafter, the other feed cable 96 is connected to the adjacent 15 arm 19 of the support structure, and the cutter bar is moved from right to left, from the position indicated at A in Fig. 4 to the position indicated at B, thereby to complete the horizontal cut. After the completion of the horizontal cut 20 the cables are rewound on their respective drums, the hooks 98 attached to the drum flanges, and the guide arms are folded against the sides of the machine body.

When it is desired to make a shearing or vertical cut in the coal face, the operator turns the hand wheel 85 to move the cutter bar through an arc of a circle from the full line position shown in Fig. 12 to one or the other of the dotted line positions indicated in that figure. The operator 30 then turns the hand wheel 80, thereby swinging the cutter bar to the position indicated at D in Fig. 1. The machine is then fed bodily along the mine trackway until the cutter bar assumes a position closely adjacent the face of the coal, 35 and thereafter the cutter bar is swung downwardly in its plane by suitable manipulation of the hand wheel 80 to effect its shearing cut. Under certain conditions, the cutter bar when disposed in its vertical or shearing position may be swung 40 upwardly to the position indicated at E in Fig. 1, and thereafter the machine may be fed bodily along the mine trackway to cause the cutter bar to penetrate the wall of coal. After completion 45 of the dumping cut, the cutter bar may be swung 50 downwardly in its plane and thereafter the machine may be fed bodily rearwardly to withdraw the cutter bar from the coal. As the machine herein described operates to cut kerfs in both 55 vertical and horizontal planes in accordance with the standard arc wall practice, further description of the mode of operation of the machine is unnecessary. These and various other methods of use of the improved mining machine will be clearly apparent to those skilled in the art.

As a result of this invention it will be noted that an improved coal mining machine is provided of the combined horizontal and shear cutter type, whereby both horizontal and vertical kerfs may 60 be cut in the coal face and whereby a horizontal cut of substantially uniform depth may be made completely across the face of the coal. It will further be noted that by the provision of the improved adjustable parallel motion support structure for the cutter head it is possible to insert vertical or shear cuts at either rib of the entry or at any point intermediate the ribs. Further, by the provision of the improved adjustable supporting structure for the cutting mechanism, it 65 is possible to move the cutter bar through a comparatively wide range, thereby enabling the machine to accommodate itself to entries of various widths.

While I have in this application specifically 75

described one form which my invention may assume in practice, it will be understood that this form is shown for purposes of illustration only, and that the invention may be embodied in various other forms without departing from its spirit or the scope of the appended claims.

What I claim as new and desire to secure by Letters Patent is:

1. In a mining machine, a portable base, an adjustable supporting arm structure mounted on said base to swing horizontally relative thereto and comprising spaced parallel horizontally disposed arms pivotally connected to the base to swing about parallel vertical axes, and a kerf cutting mechanism mounted on the outer extremity of and wholly supported by said arm structure and including a kerf cutter adjustable bodily relative to the arm structure into different cutting positions, said arms arranged in parallel relation and pivotally connected to the cutting mechanism about parallel vertical axes, the axes at the opposite ends of said arms being spaced at equal distances apart and said arms always maintaining the kerf cutter, in any of aforesaid cutting positions, parallel to a line extending longitudinally of the machine during swinging of the arms horizontally from one side of said base to the other.
2. In a mining machine, a portable base, a supporting arm structure pivotally mounted on said base to swing horizontally relative thereto and comprising spaced parallel horizontally disposed arms pivotally connected to the base to swing about parallel vertical axes, and kerf cutting mechanism mounted on the outer extremity of and wholly supported by said arm structure and including a rotatable cutter head and a kerf cutter pivotally mounted on said cutter head, said kerf cutter adjustable with said head into different cutting positions about the head axis, said arms arranged in parallel relation and pivotally connected to the cutting mechanism about parallel vertical axes, the axes at the opposite ends of said arms being spaced at equal distances apart and said arms always maintaining the cutter head axis parallel to a line extending longitudinally of the apparatus in any of aforesaid cutting positions of the kerf cutter and during swinging of said arm structure horizontally from one side of said base to the other.
3. In a mining machine, a portable base, an arm structure pivotally mounted on said base to swing horizontally relative thereto, a cutter head rotatably mounted on the outer extremity of said arm structure, and a kerf cutter pivotally mounted on said cutter head and adjustable with said cutter head relative to said arm structure into horizontal and vertical cutting positions, said arm structure always maintaining said kerf cutter parallel to a longitudinally extending plane during swinging of said arm structure.
4. In a mining machine, a portable base, a parallel link structure pivotally mounted on said base to swing horizontally about parallel vertical axes relative thereto, and kerf cutting mechanism mounted on the outer extremity of said link structure and adjustable relative thereto into horizontal and vertical cutting positions.
5. In a mining machine, a portable base, a parallel link supporting structure pivotally mounted on said base to swing horizontally relative thereto and comprising spaced parallel horizontally disposed links pivotally connected to the base to swing about parallel vertical axes, a frame carried at the outer extremity of and wholly supported by said link structure, and kerf cutting mechanism mounted on said frame and including a cutter head rotatably mounted on said frame and a kerf cutter pivotally mounted on said cutter head and adjustable with said cutter head about the head axis into different cutting positions, said links arranged in parallel relation and pivotally connected to said frame about parallel vertical axes, the axes at the opposite ends of said links being spaced at equal distances apart.
6. In a mining machine, a portable base, a parallel link structure pivotally mounted on said base to swing horizontally about parallel vertical axes relative thereto, a frame carried at the outer extremity of said link structure, a cutter head rotatably mounted on said frame, and a kerf cutter pivotally mounted on said cutter head and adjustable with said cutter head relative to said links into horizontal and vertical cutting positions.
7. In a mining machine, a portable base, an arm structure pivotally mounted on said base to swing relative thereto, kerf cutting mechanism mounted on the outer extremity of said arm structure and adjustable relative thereto into horizontal and vertical cutting positions, and means supplemental to said arm structure for supporting said cutting mechanism during swinging of said arm structure relative to said base.
8. In a mining machine, a portable base, a parallel link structure pivotally mounted on said base and comprising pairs of parallel links, and kerf cutting mechanism mounted on the outer extremity of said link structure and adjustable relative thereto into horizontal and vertical cutting positions.
9. In a mining machine, a portable base, a parallel link structure pivotally mounted on said base and comprising pairs of parallel links, a cutter head rotatably mounted on the outer extremity of said link structure, and a kerf cutter pivotally mounted on said cutter head and adjustable with said cutter head relative to said link structure into horizontal and vertical cutting positions.
10. In a mining machine, a portable base, kerf cutting mechanism on said base including an elongated kerf cutter, and adjustable supporting means for said kerf cutter swingable horizontally relative to said base for moving said kerf cutter during such horizontal swinging movement laterally in a substantially straight path while said cutter remains all the time parallel to a longitudinally extending vertical plane to cut a horizontal kerf of substantially uniform depth in the coal face, said supporting means including means for positioning said kerf cutter in a horizontal cutting position and for positioning said kerf cutter in a position to cut an angularly disposed kerf.
11. In a mining machine, a portable base, kerf cutting mechanism on said base including an elongated kerf cutter, and adjustable supporting means for said kerf cutter swingable horizontally relative to said base for moving said kerf cutter during such horizontal swinging movement laterally in a substantially straight path while said cutter remains all the time parallel to a longitudinally extending vertical plane to cut a horizontal kerf of substantially uniform depth in the coal face, said supporting means including means for positioning said kerf cutter in a horizontal cutting position and for positioning said kerf cutter in a position to cut a vertical kerf.
12. In a mining machine, a portable base, kerf cutting mechanism thereon including an elongated kerf cutter, adjustable supporting means for said kerf cutter for positioning said kerf cutter

- to cut in a horizontal plane or in a vertical plane, and mechanism mounted on said base to swing horizontally relative thereto for moving said kerf cutter during such horizontal swinging movement in its horizontal plane laterally in a substantially straight path while said kerf cutter remains at all times parallel to a longitudinally extending vertical plane to cut a kerf of a uniform depth across the coal face.
13. In a mining machine, a portable base, kerf cutting mechanism thereon including an elongated pivoted kerf cutter mounted for swinging movement relative to said base, adjustable supporting means for said kerf cutter for positioning said kerf cutter to operate in angularly disposed planes, mechanism mounted on said base to swing horizontally relative thereto for moving said kerf cutter during such horizontal swinging movement in one of its planes laterally in a substantially straight path while said kerf cutter at all times remains stationary as regards pivotal movement to cut a kerf of a substantially uniform depth across the coal face, and means for swinging said kerf cutter about its pivot in its angularly disposed plane.
14. In a mining machine, a portable base, a kerf cutting mechanism thereon including an elongated pivoted kerf cutter swingable relative to said base, adjustable supporting means for said kerf cutter including means for positioning said kerf cutter to cut a kerf in a horizontal plane or in a vertical plane, mechanism mounted on said base to swing horizontally relative thereto for moving said kerf cutter during such horizontal swinging movement in its horizontal plane laterally in a substantially straight path while said kerf cutter at all times remains stationary as regards pivotal movement to cut a kerf of a substantially uniform depth across the coal face, and mechanism for swinging said kerf cutter about its pivot to cut a vertical kerf.
15. In a mining machine, a portable base, kerf cutting mechanism thereon including an elongated kerf cutter, adjustable supporting means for said kerf cutter on which said kerf cutter is pivotally mounted for swinging movement relative thereto, means mounted on said base to swing horizontally relative thereto for moving said kerf cutter during such horizontal swinging movement laterally in a substantially straight path while said kerf cutter at all times extends parallel to a longitudinally extending vertical plane to cut a kerf of a substantially uniform depth across the coal face, and means for independently swinging said cutter bar about its pivot to make an arcuate cut.
16. In a mining machine, a portable base, kerf cutting mechanism thereon including an elongated kerf cutter, a motor on said base, adjustable supporting means for said kerf cutter mounted on said base for horizontal swinging movement relative thereto including means for adjusting said kerf cutter into a position to cut a horizontal kerf and for moving said kerf cutter during horizontal swinging movement of said supporting means laterally in a substantially straight path while the major axis of said kerf cutter always remains perpendicular to the coal face to cut a horizontal kerf of a substantially uniform depth across the coal face and for positioning said kerf cutter to cut a vertical kerf, and driving connections between said motor and said kerf cutter.
17. In a mining machine, a portable base, kerf cutting mechanism adjustably mounted thereon including an elongated kerf cutter, mechanism on said base for adjusting said kerf cutter into horizontal and vertical positions, and mechanism mounted on said base for horizontal swinging movement relative thereto for moving said kerf cutter during such horizontal swinging movement in one of its positions laterally in a substantially straight path while said kerf cutter always remains parallel to a longitudinally extending vertical plane to cut a substantially straight face kerf of a substantially uniform depth across the coal face.
18. In a mining apparatus, a portable base, an adjustable supporting structure comprising parallel links pivotally connected to said base to swing horizontally relative thereto about parallel vertical axes, a frame supported by said links, said links pivotally connected to said frame about parallel vertical axes and the axes at the opposite ends of said links being spaced at equal distances apart, a cutter head mounted on said frame for rotation relative thereto about a horizontal axis, a kerf cutter pivotally mounted on said cutter head and adjustable with said head about the head axis into different cutting positions, and devices for rotating said cutter head about its axis relative to said frame.
19. In a mining apparatus, a portable base, parallel links pivotally connected to said base to swing horizontally relative thereto about parallel vertical axes, a frame supported by said links, a cutter head mounted on said frame for rotation relative thereto about a horizontal axis, a kerf cutter pivotally mounted on said cutter head, and devices for swinging said kerf cutter about its pivot relative to said cutter head.
20. In a mining apparatus, a portable base, parallel links pivotally connected to said base to swing horizontally relative thereto about parallel vertical axes, a frame supported by said links, a cutter head mounted on said frame for rotation relative thereto about a horizontal axis, a kerf cutter pivotally mounted on said cutter head, devices for rotating said cutter head about its axis relative to said frame, and devices for swinging said kerf cutter about its pivot relative to said cutter head.
21. In a mining apparatus, a portable base, a kerf cutter adjustable into horizontal and vertical cutting positions, an adjustable supporting structure plurally articulated to said base on parallel pivots and supporting said kerf cutter when the latter is in its vertical cutting position for adjustment into parallel vertical planes, said kerf cutter being adjustable relative to said supporting structure into aforesaid cutting positions, and means for adjusting said supporting structure about its plural articular connections with said base to effect aforesaid adjustment of said kerf cutter into parallel vertical planes.
22. In a mining apparatus, a portable base, a frame, a rotatable cutter head mounted on said frame for rotation relative thereto, a kerf cutter pivotally mounted on said cutter head, an adjustable supporting structure plurally articulated to said base on parallel pivots and supporting said frame for adjusting said cutter head laterally relative to said base, and means for adjusting said supporting structure about its plural articular connections with said base to effect aforesaid adjustment of said cutter head into different lateral positions.
23. In a mining apparatus, a portable base, an arm structure pivotally mounted on said base to swing horizontally relative thereto, a frame sup-

ported on the outer extremity of said arm structure and to which said arm structure is pivotally connected, said frame being swingable relative to said arm structure, said arm structure and frame constituting a parallel motion device having provision for maintaining parallelism selectively to different angularly related horizontal lines, a cutter head mounted on said frame for rotation relative thereto about a horizontal axis 5 extending longitudinally of the apparatus when said arm structure is in mid position between the sides of said base, a kerf cutter pivotally mounted on said cutter head, and devices for rotating said cutter head about its axis and for swinging said kerf cutter about its pivot.

24. In a mining apparatus, a portable base, an arm structure pivotally mounted on said base to swing horizontally relative thereto, a frame supported on the outer extremity of said arm structure and to which said arm structure is pivotally connected, said frame being swingable relative to said arm structure about an axis parallel with the pivotal axis of the arm structure, said arm structure and frame constituting a parallel motion device having provision for maintaining parallelism selectively to different angularly related horizontal lines, a cutter head mounted on said frame for rotation relative thereto about a horizontal axis, a kerf cutter pivotally mounted on said cutter head about its axis and for swinging said kerf cutter about its pivot, and motor operated devices for swinging said arm structure horizontally relative to said base.

35 25. In a mining apparatus, a portable base, an arm structure pivotally mounted on said base to swing horizontally relative thereto, a frame supported on the outer extremity of said arm structure and to which said arm structure is pivotally connected, said frame being swingable relative to said arm structure, a cutter head mounted on said frame for rotation relative thereto about a horizontal axis extending longitudinally of the apparatus when said arm structure is in mid-position between the sides of the base, a kerf cutter pivotally mounted on said cutter head, devices for rotating said cutter head about its axis and for swinging said kerf cutter about its pivot, and motor operated devices for swinging said arm structure horizontally relative to said base and including a motor supported on said base and relative to which said arm structure is swingable.

55 26. In a mining apparatus, a portable base, parallel supporting links pivotally connected to said base to swing horizontally relative thereto about parallel vertical axes, a frame supported by said links, said links pivotally connected to said frame about parallel vertical axes and the axes at the opposite ends of said links being spaced at equal distances apart, a cutter head mounted on said frame for rotation relative thereto about a horizontal axis, and a kerf cutter pivotally mounted on said cutter head and adjustable with said head about the head axis into different cutting positions, said parallel links maintaining said cutter head axis always parallel to a common straight line during swinging of said links horizontally about their pivots.

70 27. In a mining apparatus, a portable base, a parallel motion arm structure overhanging said base and pivotally mounted at its rearward extremity on said base to swing in a horizontal direction relative thereto about parallel vertical axes, and a kerf cutter mounted on the outer overhanging extremity of said arm structure and

adjustable relative to said arm structure into horizontal and vertical cutting positions.

28. In a mining apparatus, a portable base, a parallel motion arm structure overhanging said base and pivotally mounted at its rearward extremity on said base to swing in a horizontal direction relative thereto about parallel vertical axes, a cutter head mounted on the outer overhanging extremity of said arm structure for rotation relative thereto about a horizontal axis, 10 and a kerf cutter pivotally mounted on said cutter head and rotatable therewith about the head axis relative to said arm structure into horizontal and vertical cutting positions.

15 29. In a mining apparatus, a portable base, parallel supporting links pivotally connected to said base for swinging movement in a horizontal direction relative thereto about parallel vertical axes, a frame supported by said links, said links pivotally connected to said frame about parallel 20 vertical axes and the axes at the opposite ends of said links being spaced at equal distances apart, a cutter head mounted on said frame for rotation relative thereto about a horizontal axis, and a kerf cutter pivotally mounted on said cutter head 25 and adjustable with said head about the head axis into different cutting positions.

30 30. In a mining apparatus, a portable base, a parallel motion arm structure including an arm element pivotally mounted on the forward end of said base to swing in a horizontal direction relative thereto about a vertical axis, a kerf cutter mounted on the outer extremity of said arm structure and adjustable relative thereto into horizontal and vertical cutting positions, a motor carried by said base and relative to which said arm structure is swingable, and devices driven by said motor for actuating said kerf cutter.

35 31. In a mining apparatus, a portable base, an arm structure including an arm element pivotally mounted on the forward end of said base to swing in a horizontal direction relative thereto about a vertical axis, a kerf cutter mounted on the outer extremity of said arm structure and adjustable relative thereto into horizontal and vertical cutting positions, a motor carried by said base relative to which said arm structure is swingable and whose position does not change with any change in position of said kerf cutter relative to said base, devices driven by said motor for actuating said kerf cutter, and devices driven by said motor for swinging said arm structure relative to said base.

40 32. In a mining apparatus, a portable base, an arm structure including an arm element pivotally mounted on the forward end of said base to swing in a horizontal direction relative thereto about a vertical axis, a cutter head mounted on the outer extremity of said arm structure for rotation relative thereto about a horizontal axis, and a kerf cutter pivotally mounted on said cutter head and rotatable therewith relative to said arm structure into horizontal and vertical cutting positions, said arm structure constituting mechanism for automatically maintaining the axis of said cutter head parallel to a common straight line during swinging of said arm structure.

45 33. In a mining apparatus, a portable base, a supporting structure mounted on said base including parallel arms pivotally mounted on the forward end of said base for swinging movement relative thereto about vertical axes, and a kerf cutter mounted on the outer extremities of said arms for adjustment relative thereto into horizontal and vertical cutting positions.

34. In a mining apparatus, a portable base, a supporting structure mounted on said base including spaced parallel arms pivotally mounted on the forward end of said base for swinging movement relative thereto about vertical axes, a kerf cutter mounted on the outer extremities of said arms for adjustment relative thereto into horizontal and vertical cutting positions, and devices for adjusting said arms to vary their parallel relationship to effect adjustment of the kerf cutter angularly relative to the vertical.

35. In a mining apparatus, a portable base, an adjustable supporting structure including parallel arms pivotally mounted on the forward end of said base for swinging movement relative thereto about vertical axes, and a kerf cutter mounted on the outer extremity of said supporting structure for adjustment relative thereto into horizontal and vertical cutting positions, said arms maintaining automatically said kerf cutter parallel to a common straight line during swinging of said arms about their pivots relative to said base.

36. In a mining apparatus, a portable base, an adjustable supporting structure including parallel arms pivotally mounted on the forward end of said base for swinging movement relative thereto about vertical axes, a cutter head mounted on the outer extremity of said supporting structure for rotation relative thereto about a horizontal axis, and a kerf cutter pivotally mounted on said cutter head and rotatable therewith relative to said supporting structure into horizontal and vertical cutting positions.

37. In a mining apparatus, a portable base, an adjustable supporting structure including parallel arms pivotally mounted on the forward end of said base for swinging movement relative thereto about vertical axes, a cutter head mounted on the outer extremity of said supporting structure for rotation relative thereto about a horizontal axis, a kerf cutter pivotally mounted on said cutter head and rotatable therewith relative to said supporting structure into horizontal and vertical cutting positions, and devices for adjusting said arms to vary their parallel relationship to effect movement of said kerf cutter angularly relative to the vertical.

38. In a mining apparatus, a portable base, an adjustable supporting structure including parallel arms pivotally mounted on the forward end of said base for swinging movement relative thereto about vertical axes, a cutter head mounted on the outer extremities of said arms for rotation relative thereto about a horizontal axis, and a kerf cutter pivotally mounted on said cutter head and rotatable therewith relative to said supporting structure into horizontal and vertical cutting positions and said arms maintaining automatically said cutter head axis parallel to a common straight line during swinging of said arms about their pivots relative to said base.

39. In a mining apparatus, a portable base, a rotatable cutter head, a kerf cutter pivotally mounted on said head, and an adjustable supporting structure between said base and cutter head by which the latter is supported and relative to which said head is rotatable for swinging said cutter head laterally in either direction relative to said base while the head axis always remains parallel to a horizontal line extending longitudinally of the apparatus, said supporting structure comprising spaced parallel horizontally disposed arms pivotally connected at their opposite ends to the base and head about parallel

vertical axes, the axes at the opposite ends of said arms being spaced at equal distances apart.

40. In a mining apparatus, a portable base, a kerf cutter, an adjustable supporting structure between said base and kerf cutter including an arm pivotally connected to said base, devices for swinging said arm about its pivot to move said kerf cutter laterally relative to said base, linkage devices for maintaining said kerf cutter at all times parallel to a common straight line during such lateral adjustment, and devices carried at the outer end of said arm for adjusting said kerf cutter into horizontal and vertical cutting positions.

41. In a mining apparatus, a portable base, a kerf cutter, an adjustable supporting structure between said base and said kerf cutter for swinging said kerf cutter about a vertical axis on said base into different lateral positions while said kerf cutter at all times automatically remains parallel to a common straight line, and devices on the outer extremity of said supporting structure for adjusting said kerf cutter into horizontal and vertical cutting positions.

42. In a mining apparatus, a portable base, a horizontal kerf cutter, and an adjustable double parallelogram supporting structure mounted on said base and carrying said kerf cutter, said kerf cutter always extending parallel to a longitudinally extending plane during adjustment of said supporting structure.

43. In a mining machine, a portable base, an adjustable arm structure mounted on said base to swing horizontally relative thereto, kerf cutting mechanism including a kerf cutter mounted on the outer extremity of said arm structure for adjustment bodily relative thereto into horizontal and vertical cutting positions, said cutting mechanism and arm structure being adjustable relative to said base to enable the kerf cutter to cut parallel vertical kerfs parallel to the longitudinal median line of the base between the sides of said base and beyond the sides of said base, all while said kerf cutter remains in vertical cutting position, a motor on said base and relative to which said arm structure is swingable for adjusting said arm structure and kerf cutter and for actuating said kerf cutter and means for adjusting said kerf cutter relative to said arm structure.

44. In a mining machine, a portable base, an adjustable arm structure mounted on said base to swing horizontally relative thereto, kerf cutting mechanism including a cutter head rotatably mounted on the outer extremity of said arm structure and a kerf cutter mounted on said cutter head and adjustable with said head into different cutting positions completely about the head axis, said cutting mechanism and arm structure being adjustable relative to said base to position the kerf cutter to cut parallel vertical kerfs parallel to the longitudinal median line of the base between the sides of said base and beyond the sides of said base, all while said kerf cutter remains in vertical cutting position, a motor on said base and relative to which said arm structure is swingable for adjusting said arm structure and for actuating said kerf cutter, and means for rotating said cutter head.

45. In a mining machine, a portable base, an adjustable arm structure mounted on said base to swing horizontally relative thereto, kerf cutting mechanism including a cutter head rotatably mounted on the outer extremity of said arm structure and a kerf cutter mounted on said cutter head for adjustment bodily relative thereto into

different cutting positions, said cutting mechanism and arm structure being adjustable relative to said base to position the kerf cutter to cut parallel vertical kerfs parallel to the longitudinal median line of the base between the sides of said base and beyond the sides of said base, all while said kerf cutter remains in vertical cutting position, a motor on said base and relative to which said arm structure is swingable for swinging said arm structure and kerf cutter and for actuating said kerf cutter, and means for adjusting said kerf cutter relative to said arm structure.

46. In a mining machine, a portable base, a parallel motion supporting structure mounted on said base for adjustment horizontally relative thereto about parallel vertical axes, a frame carried at the outer extremity of said supporting structure, a cutter head rotatably mounted on said frame, and a kerf cutter pivotally mounted on said cutter head and adjustable with said head about the head axis.

47. A coal cutting machine comprising a body, a cutter bar mounted on said body for pivotal movement about two separate axes one of which extends at all times vertically and the other of which is adjustable between vertically and horizontally extending positions, and means including a swinging frame mounted on said body for shifting said first mentioned axis transversely of the machine to positions outside the lateral limits of the body at either side of the latter.

48. A coal cutting machine comprising a body, a motor mounted on said body and having its axis of driving shaft rotation permanently fixed against motion with respect to said body, a cutter bar mounted on said body for pivotal movement about two separate axes each of which extends at all times transversely with respect to the longitudinal axis of the machine and one of which is adjustable between vertically and horizontally extending positions, means including a swinging frame mounted on said body for shifting said axes transversely of the machine, said cutter bar including a movable cutting element, and a constant driving connection between said motor and said cutting element.

49. A coal cutting machine comprising a body, a member mounted on said body for swinging adjustment bodily transversely of the machine and for pivotal adjustment about a vertical axis in any position of adjustment thereof transversely of the machine, said member having a range of swinging adjustment to position said vertical axis outside the lateral limits of the machine body at either side of the latter, a second member mounted on said first member for pivotal adjustment with respect thereto about an axis disposed at right angles to the axis of pivotal movement of said first mentioned member, and a cutter bar mounted on said second mentioned member for pivotal adjustment about an axis disposed at right angles to the axis of the pivotal connection between said members.

50. A coal cutting machine comprising a body, a member mounted on said body for swinging adjustment bodily transversely of the machine and for pivotal adjustment about a vertical axis in any position of adjustment thereof transversely of the machine, said member having a range of swinging adjustment to position said vertical axis outside the lateral limits of the machine body at either side of the latter, a second member mounted on said first member for pivotal adjustment with respect thereto about an axis disposed at

right angles to the axis of pivotal movement of said first mentioned member, a cutter bar mounted on said second mentioned member for pivotal adjustment about an axis disposed at right angles to the axis of the pivotal connection between said members, and means on the body for pivotally adjusting said first mentioned member.

51. A coal cutting machine comprising a body, a member mounted on said body for swinging adjustment bodily transversely of the machine and for pivotal adjustment about a vertical axis in any position of adjustment thereof transversely of the machine, said member having a range of swinging adjustment to position said vertical axis outside the lateral limits of the machine body at either side of the latter, a second member mounted on said first member for pivotal adjustment with respect thereto about an axis disposed at right angles to the axis of pivotal movement of said first mentioned member, a cutter bar mounted on said second mentioned member for pivotal adjustment about an axis disposed at right angles to the axis of the pivotal connection between said members, and means on said first mentioned member for pivotally adjusting said second member with respect thereto.

52. A coal cutting machine comprising a body, a member mounted on said body for swinging adjustment bodily transversely of the machine and for pivotal adjustment about a vertical axis in any position of adjustment thereof transversely of the machine, said member having a range of swinging adjustment to position said vertical axis outside the lateral limits of the machine body at either side of the latter, a second member mounted on said first member for pivotal adjustment with respect thereto about an axis disposed at right angles to the axis of pivotal movement of said first mentioned member, a cutter bar mounted on said second mentioned member for pivotal adjustment about an axis disposed at right angles to the axis of the pivotal connection between said members, and means on said second mentioned member for pivotally adjusting said cutter bar with respect thereto.

53. A coal cutting machine comprising a body, a member mounted on said body, a pair of arms pivotally connected at adjacent ends to said member at spaced points, respectively, a second member to which the opposite ends of said arms are pivotally connected at spaced points, respectively, a second pair of arms pivotally connected at adjacent ends to said second member on pivots coaxial with the pivotal connections of said first pair of arms therewith, a third member to which the opposite ends of said second pair of arms are pivotally connected at spaced points, respectively, and a cutter bar carried by said third member.

54. A coal cutting machine comprising a body, a member mounted on said body for rotary adjustment about a vertical axis, a pair of arms pivotally connected at adjacent ends to said member at spaced points, respectively, a second member to which the opposite ends of said arms are pivotally connected at spaced points, respectively, a second pair of arms pivotally connected at adjacent ends to said second member on pivots coaxial with the pivotal connections of said first pair of arms therewith, a third member to which the opposite ends of said second pair of arms are pivotally connected at spaced points, respectively, a cutter bar carried by said third member, and means for rotatably adjusting said first mentioned member.

55. A coal cutting machine comprising a body, a member mounted on said body, a pair of arms pivotally connected at adjacent ends to said member at spaced points, respectively, a second member to which the opposite ends of said arms are pivotally connected at spaced points, respectively, whereby said second member is mounted for bodily shifting movement with respect to the body of the machine, a cutter bar connected with said second mentioned member, said first mentioned member being mounted on said body for rotary adjustment, and means for rotatably adjusting said first mentioned member thereby to rotatably adjust said second mentioned member and said cutter bar in any bodily adjusted position of said second mentioned member and said cutter bar.
56. In a mining machine, a portable base, an adjustable supporting arm structure mounted on said base to swing horizontally relative thereto, and a kerf cutter mounted on the outer extremity of and supported by said arm structure for adjustment bodily relative thereto into parallel planes, said arm structure always automatically maintaining said kerf cutter parallel to a line extending longitudinally of the machine during swinging of said arm structure.
57. In a mining machine, a portable base, a supporting arm structure pivotally mounted on said base to swing horizontally relative thereto, a cutter head rotatably mounted on the outer extremity of and supported by said arm structure, and a kerf cutter pivotally mounted on said cutter head and adjustable with the head about the head axis into parallel planes, said arm structure always automatically maintaining the cutter head axis parallel to a line extending longitudinally of the machine during swinging of said arm structure.
58. In a mining apparatus, a portable base, a rotatable cutter head, a kerf cutter pivotally mounted on said head and adjustable with said head about the head axis into parallel planes, and an adjustable supporting structure between said base and cutter head by which the latter is supported and relative to which said head is rotatable for swinging said cutter head laterally in either direction relative to said base while the head axis automatically always remains parallel to a horizontal line extending longitudinally of the apparatus.
59. In a mining machine, a portable base, an adjustable supporting arm structure mounted on said base to swing horizontally relative thereto, and a kerf cutter mounted on the outer extremity of and supported by said arm structure and adjustable bodily relative to the arm structure into different cutting positions while the kerf cutter remains at all times parallel to a line extending longitudinally of the base, said arm structure always maintaining said kerf cutter parallel to a line extending longitudinally of the machine during swinging of said arm structure horizontally from one side of said base to the other.
60. In a mining machine, a portable base, a supporting arm structure pivotally mounted on said base to swing horizontally relative thereto, a cutter head rotatably mounted on the outer extremity of and supported by said arm structure, and a kerf cutter pivotally mounted on said cutter head and adjustable with said head about the head axis into different cutting positions while the kerf cutter remains at all times parallel to a line extending longitudinally of said base, said arm structure always maintaining the cutter head axis parallel to a line extending longitudinally of the machine during swinging of said arm structure horizontally from one side of said base to the other.
61. In a mining machine, a portable base, a parallel link supporting structure pivotally mounted on said base to swing horizontally relative thereto, a frame carried at the outer extremity of and supported by said link structure, a cutter head rotatably mounted on said frame, and a kerf cutter pivotally mounted on said cutter head and adjustable with said cutter head about the head axis into different cutting positions while the kerf cutter remains at all times parallel to a line extending longitudinally of said base.
62. In a mining apparatus, a portable base, an adjustable supporting structure comprising parallel links pivotally connected to said base to swing horizontally relative thereto, a frame supported by said links, a cutter head mounted on said frame for rotation relative thereto about a horizontal axis, a kerf cutter pivotally mounted on said cutter head and adjustable with said head about the head axis into different cutting positions while said kerf cutter at all times remains parallel to a line extending longitudinally of said base, and devices for rotating said cutter head about its axis relative to said frame.
63. In a mining apparatus, a portable base, parallel supporting links pivotally connected to said base to swing horizontally relative thereto, a frame supported by said links, a cutter head mounted on said frame for rotation relative thereto about a horizontal axis, and a kerf cutter pivotally mounted on said cutter head and adjustable with said head about the head axis into different cutting positions while the kerf cutter at all times remains parallel to a line extending longitudinally of said base, said parallel links maintaining said cutter head axis always parallel to a common straight line during swinging of said links horizontally about their pivots.
64. In a mining apparatus, a portable base, parallel supporting links pivotally connected to said base for swinging movement in a horizontal direction relative thereto, a frame supported by said links, a cutter head mounted on said frame for rotation relative thereto about a horizontal axis, and a kerf cutter pivotally mounted on said cutter head and adjustable with the head about the head axis while the kerf cutter always remains parallel to a line extending longitudinally of the apparatus.
65. In a mining apparatus, a portable base, a rotatable cutter head, a kerf cutter pivotally mounted on said cutter head and adjustable with said head about the head axis into different cutting positions while the kerf cutter at all times remains parallel to a line extending longitudinally of said base, and an adjustable parallel motion supporting structure between said base and cutter head by which the latter is supported and relative to which said head is rotatable for swinging said cutter head laterally in either direction relative to the base while the head axis always remains parallel to a horizontal line extending longitudinally of the apparatus.
66. In a mining apparatus, a portable base, a parallel motion device including an arm pivotally mounted on said base and a second arm pivotally supported on said first arm about an axis parallel with the pivotal axis of the first arm, said second arm overhanging said base, and

5 a kerf cutter pivotally mounted on the forward overhanging extremity of said second arm, said arms being adjustable about their pivotal axes to move said kerf cutter horizontally to cut a horizontal kerf and said second arm being swingable relative to said first arm to swing said kerf cutter horizontally relative to said base, and means for adjusting said arms relative to said base.

10 67. In a mining apparatus, a portable base, a parallel motion device including an arm pivotally mounted on said base and a second arm pivotally supported on said first arm about an axis parallel with the pivotal axis of the first arm, said second arm overhanging said base, and a kerf cutter pivotally mounted on the forward overhanging extremity of said second arm, said arms being adjustable about their pivotal axes to move said kerf cutter horizontally to cut a horizontal kerf, and means for adjusting said arms relative to said base, said second arm being swingable horizontally relative to the first arm while the latter remains stationary as regards swinging movement about its own axis.

15 68. In a mining apparatus, a portable base, a parallel motion device including an arm pivotally mounted on said base and a second arm pivotally mounted on said first arm, said second arm overhanging said base, a cutter head rotatably mounted on the outer overhanging extremity of said second arm, and a kerf cutter pivotally mounted on said cutter head and adjustable with said head about the head axis into different cutting positions, said arms being adjustable to move said kerf cutter into different cutting positions, and means for adjusting said arms relative to said base.

20 69. In a mining apparatus, a portable base, a parallel motion device including an arm pivotally mounted on said base and a second arm pivotally mounted on said first arm, said second arm overhanging said base, a cutter head rotatably mounted on the outer overhanging extremity of said second arm, and a kerf cutter pivotally mounted on said cutter head and adjustable with said head about the head axis into different cutting positions, said arms being adjustable to move said kerf cutter into different cutting positions, and means for adjusting said arms relative to said base, said second arm being swingable 25 relative to the first arm while the latter remains stationary as regards swinging movement about its own axis.

25 70. In a mining apparatus, a portable base, an arm pivotally mounted at its forward end at the forward end of said base, a second arm supported by said first arm and pivotally mounted at its rear end on the rear end of said first arm, said second arm extending forwardly in advance of said base, and a kerf cutter pivotally mounted on the outer extremity of said second arm.

30 71. In a mining apparatus, a portable base, a parallel motion arm structure pivotally mounted on said base for horizontal swinging movement relative thereto, a cutter head rotatably mounted on the forward extremity of said arm structure, a kerf cutter pivotally mounted on said cutter head and adjustable with the head about the head axis into horizontal and vertical cutting positions, said arm structure during swinging movement thereof from one side of said base to the other always maintaining said head axis parallel to a line extending longitudinally of said base, and means for adjusting said head axis out of parallelism with said longitudinally extending line.

35 72. In a mining apparatus, a portable base, an arm structure pivotally mounted on said base to swing horizontally relative thereto about a vertical axis, a frame supported on the outer extremity of said arm structure and to which said arm structure is pivotally connected, said frame being swingable about a parallel axis relative to said arm structure and said arm structure providing a parallel motion device connecting said frame to said base, a cutter head mounted on said frame for rotation relative thereto about a horizontal axis, a kerf cutter pivotally mounted on said cutter head, and devices for rotating said cutter head about its axis and for swinging said kerf cutter about its pivot.

40 73. In a mining apparatus, a portable base, an arm structure pivotally mounted on said base to swing horizontally relative thereto about a vertical axis, a frame supported on the outer extremity of said arm structure and to which said arm structure is pivotally connected, said frame being swingable about a parallel axis relative to said arm structure and said arm structure providing a parallel motion device connecting said frame to said base, a cutter head mounted on said frame for rotation relative thereto about a horizontal axis, a kerf cutter pivotally mounted on said cutter head, devices for rotating said cutter head about its axis and for swinging said kerf cutter about its pivot, and motor operated devices for swinging said arm structure horizontally relative to said base.

45 74. In a mining apparatus, a portable base, an arm structure pivotally mounted on said base to swing horizontally relative thereto about a vertical axis, a frame supported on the outer extremity of said arm structure and to which said arm structure is pivotally connected, said frame being swingable about a parallel axis relative to said arm structure, a cutter head mounted on said frame for rotation relative thereto about a horizontal axis, a kerf cutter pivotally mounted on said cutter head, devices for rotating said cutter head about its axis and for swinging said kerf cutter about its pivot, and motor operated devices for swinging said arm structure horizontally relative to said base and including a motor supported on said base and relative to which said arm structure is swingable.

50 75. In a mining apparatus, a portable base, an arm structure pivotally mounted on said base for horizontal swinging movement relative thereto about a vertical axis, a frame supported on the outer extremity of said arm structure and to which the latter is pivotally connected, said frame being swingable about a parallel axis relative to said arm structure and said arm structure providing a parallel motion device connecting said frame to said base, a cutter head supported by said frame for rotation relative thereto about a horizontal axis, a kerf cutter mounted on said cutter head and adjustable with said head into horizontal and vertical cutting positions, devices for rotating said head about its axis, and motor operated devices for driving said kerf cutter.

55 76. In a mining apparatus, a portable base, an arm structure including an arm element pivotally mounted on the forward end of said base to swing in a horizontal direction relative thereto about a vertical axis, kerf cutting mechanism including a kerf cutter having orbitally movable cutting elements and mounted on the outer extremity of said arm structure and adjustable relative thereto into horizontal and vertical cutting positions, said kerf cutting mechanism and

- arm structure being adjustable relative to said base to position said kerf cutter to cut parallel vertical kerfs parallel to the longitudinal median line of said base, a motor carried by said base and relative to which said arm structure is swingable, and devices driven by said motor for actuating said kerf cutter to effect movement of its cutting elements in their orbits.
77. In a mining apparatus, a portable base, an arm structure including an arm element pivotally mounted on the forward end of said base to swing in a horizontal direction relative thereto about a vertical axis, kerf cutting mechanism including a kerf cutter mounted on the outer extremity of said arm structure and adjustable relative thereto into horizontal and vertical cutting positions, said kerf cutting mechanism and arm structure being adjustable relative to said base to position said kerf cutter to cut parallel vertical kerfs parallel to the longitudinal median line of said base, a motor carried by said base and relative to which said arm structure is swingable, devices driven by said motor for actuating said kerf cutter, and devices driven by said motor for swinging said arm structure relative to said base.
78. In a mining apparatus, a portable base, a parallel motion device including an arm pivotally mounted on said base and a second arm pivotally mounted on said first arm to swing relative thereto about an axis parallel with the pivotal axis of the first arm, said second arm overhanging said base, a cutter head rotatably mounted on the outer overhanging extremity of said second arm, and a kerf cutter pivotally mounted on said cutter head and adjustable with said head about the head axis into different cutting positions, said arms being adjustable to move said kerf cutter into different cutting positions, and means for adjusting said arms relative to said base.
79. In a mining apparatus, a portable base, a parallel motion device including an arm pivotally mounted on said base and a second arm pivotally mounted on said first arm to swing relative thereto about an axis parallel with the pivotal axis of the first arm, said second arm overhanging said base, a cutter head rotatably mounted on the outer overhanging extremity of said second arm, and a kerf cutter pivotally mounted on said cutter head and adjustable with said head about the head axis into different cutting positions, said arms being adjustable to move said kerf cutter into different cutting positions, and means for adjusting said arms relative to said base, said second arm being swingable relative to the first arm while the latter remains stationary as regards swinging movement about its own axis.
80. In a mining apparatus, a portable base, an arm structure pivotally mounted on said base to swing horizontally relative thereto, kerf cutting mechanism mounted on the outer extremity of said arm structure and including a plane kerf cutter swingable vertically to cut a vertical kerf, said kerf cutting mechanism and said arm structure being adjustable relative to said base to position the kerf cutter to cut a series of parallel vertical plane kerfs parallel to the longitudinal median line of said base and between the sides and beyond the opposite sides of said base while said kerf cutter always remains in a vertical cutting position, and means for adjusting said kerf cutting mechanism relative to said arm structure to position said kerf cutter to cut a horizontal kerf.
81. In a mining apparatus, a portable base, an arm structure pivotally mounted on said base to swing horizontally relative thereto, kerf cutting mechanism mounted on the outer extremity of said arm structure and including a plane kerf cutter having a cutter chain and swingable vertically to cut a vertical kerf, said kerf cutting mechanism and said arm structure being adjustable relative to said base to position the kerf cutter to cut a series of parallel vertical plane kerfs parallel to the longitudinal median line of said base and between the sides and beyond the opposite sides of said base, means for adjusting said kerf cutting mechanism relative to said arm structure to position said kerf cutter to cut a horizontal kerf, and a motor on said base and relative to which said arm structure is swingable for actuating the chain of said kerf cutter.
82. In a mining apparatus, a portable base, an arm structure pivotally mounted on said base to swing horizontally relative thereto, kerf cutting mechanism mounted on the outer extremity of said arm structure and including a plane kerf cutter swingable vertically to cut a vertical kerf, said kerf cutting mechanism and said arm structure being adjustable relative to said base to position the kerf cutter to cut a series of parallel vertical plane kerfs parallel to the longitudinal median line of said base and between the sides and beyond the opposite sides of said base, means for adjusting said kerf cutting mechanism relative to said arm structure to position said kerf cutter to cut a horizontal kerf, and a motor on said base and relative to which said arm structure is swingable for actuating said kerf cutter and for swinging said arm structure relative to said base.
83. In a mining apparatus, a portable base, an arm structure pivotally mounted on said base to swing horizontally relative thereto, a cutter head rotatably mounted on the outer extremity of said arm structure to rotate relative thereto about a horizontal axis, a kerf cutter pivotally mounted on said cutter head to swing relative thereto and adjustable with said head about the head axis into horizontal and vertical cutting positions, said head being adjustable relative to said arm structure and said arm structure being swingable relative to said base to position said kerf cutter to cut a series of parallel vertical kerfs parallel to the longitudinal median line of the base and from one side of the apparatus to the other and beyond the sides of said base, said kerf cutter being adjustable into aforesaid vertical cutting positions while said head remains stationary as regards rotation about its own axis.
84. In a mining apparatus, a portable base, an arm structure pivotally mounted on said base to swing horizontally relative thereto, a cutter head rotatably mounted on the outer extremity of said arm structure to rotate relative thereto about a horizontal axis, a kerf cutter having orbitally movable cutting elements and pivotally mounted on said cutter head to swing relative thereto and adjustable with said head about the head axis into horizontal and vertical cutting positions, said head being adjustable relative to said arm structure and said arm structure being swingable relative to said base to position said kerf cutter to cut a series of parallel vertical kerfs parallel to the longitudinal median line of the base and from one side of the apparatus to the other and while said head remains stationary as regards rotation about its own axis, and a motor on said base and relative to which said

arm structure is swingable for actuating said kerf cutter to effect movement of its cutting elements in their orbits.

85. In a mining apparatus, a portable base, 5 an arm structure pivotally mounted on said base to swing horizontally relative thereto, a cutter head rotatably mounted on the outer extremity of said arm structure to rotate relative thereto about a horizontal axis, a kerf cutter pivotally 10 mounted on said cutter head to swing relative thereto and adjustable with said head about the head axis into horizontal and vertical cutting positions, said head being adjustable relative to
- said arm structure and said arm structure being swingable relative to said base to position said kerf cutter to cut a series of parallel vertical kerfs parallel to the longitudinal median line of the base and from one side of the apparatus to the other and while said head remains stationary as regards rotation about its own axis, and a motor on said base and relative to which said arm structure is swingable for actuating said kerf cutter and for swinging said arm structure 10 relative to said base. 5

ALBERT C. WILCOX.
